UNITED STATES PATENT OFFICE.

HOWARD S. GIBSON, OF WASHINGTON, DISTRICT OF COLUMBIA, ASSIGNOR OF ONE-FOURTH TO DORSEY F. ASBURY AND THREE-FOURTHS TO HELEN MILLS GIBSON, BOTH OF WASHINGTON, DISTRICT OF COLUMBIA.

VEHICLE-WASHING MACHINE.

Application filed April 14, 1924. Serial No. 706,354.

My invention relates to washing apparatus, and has particular reference to improvements in machines for washing vehicles, particularly automobiles, my aim being to provide a machine for this purpose by means of which a maximum number of vehicles may be washed in a minimum amount of time and at relatively low cost.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views.

Figure 1 is a side elevation of a vehicle washing machine embodying the novel and essential features of my invention;

Figure 2, a top plan view;

Figure 3, a transverse section on the lines 3—3 of Figure 1;

Figure 4, a transverse section on the line 4—4 of Figure 1;

Figure 5, an enlarged side elevation of a portion of the machine;

Figure 6, a detail view of one of the stop devices associated with one of the fixed spray devices of the machine;

Figure 7, a view similar to Figure 6 showing the stop device moved to released position; and

Figure 8, a detail view of one of the stop devices associated with one of the movable spray devices.

Referring now to the drawings in detail, it will be observed my improved machine, in its embodiment herein illustrated, consists of a frame and that this frame is divided into or includes three separate operating stations disposed in advance of one another, so that a vehicle entering the machine at one end of the frame passes through each of said operating stations before it emerges from the machine at the other end of the frame. The frame is designated generally at 10 and the three operating stations at *a*, *b* and *c*, respectively, the first of these latter being a soaking and washing station, the second, a washing and rinsing station, and the third, a drying station. A vehicle entering the machine is halted at station *a* where

it is subjected to sprays of preferably aerated water over a suitable period of time to soften and partially remove accumulations therefrom. It then is moved to station *b* where it again is subjected to sprays of preferably aerated water over a suitable period of time to further soak and rinse the same as operators at this station manually remove any tenacious accumulations not removed at station *a*. After being thoroughly cleansed and rinsed at station *b*, it is moved to station *c* where it is subjected to sprays of warm air to dry the same before it emerges from the machine. By this method of first soaking a vehicle at one station and then moving it to a rinsing station and subsequently to a drying station, it is obvious that a maximum number of vehicles may be cleansed in a minimum amount of time, for as soon as one vehicle has been moved from station *a* to station *b*, another vehicle may be moved into station *a* to be soaked in readiness to be moved to station *b* immediately the vehicle in station *b* is moved to station *c*.

Frame 10 is composed of a plurality of uprights 11 arranged in pairs spaced longitudinally of the machine and connected by stringers 12, the uprights of each pair being spaced transversely of the machine and connected at their upper ends by preferably arched members 13.

Midway between the uprights 11 and extending longitudinally through the frame 10 is a trestle 14 composed in this instance of uprights 15 and transverse connecting members 16, and supported by this trestle are two transversely spaced tracks 17, 17 each consisting of upper and lower pairs of rails also extending longitudinally through the machine.

Supported on the tracks 17, 17 is an endless conveyor composed in this instance of two link belts 18, 18 each of which is provided with numerous supporting wheels or rollers engaging the tracks 17, 17 whereby the belts are freely movable over said tracks. At each end of the machine is a sprocket wheel or wheels 19 over which the belts 18, 18 extend and arranged to drive the sprocket wheel or wheels at one end of the frame, whereby the belts 18, 18 are caused to be moved along the tracks 17, 17, is a motor or other suitable power device 20.

The conveyor belts 18, 18 are adapted to

be engaged by the wheels of a vehicle, whereby a vehicle may be moved bodily through the machine, or its wheels rotated when it is held against such bodily movement, and 5 in order to prevent lateral movement of a vehicle off of said belts, guard plates 21, 21 are provided, the same extending above the belts and contiguous thereto along their adjacent or inner edges preferably throughout 10 the length of the machine.

Supported by hangers or brackets 22 above and outwardly of the belts 18, 18, respectively, is a pair of operator supporting platforms 23, 23 and directly below these platforms are other operator supporting platforms 24, 24, this arrangement permitting workmen to easily reach all parts of a vehicle as is manifest.

A water supply pipe extends longitudinally of the machine at the tops of operating stations *a* and *b* and is provided at suitably spaced intervals therealong with spray heads 25, while connected with said supply pipe are branch pipes 26 leading to front and 25 rear wheel spray devices 27 and 28, respectively, provided at each side of both of said operating stations.

At each side of operating station *c* are front and rear wheel spray devices 29 and 30, respectively, designed to supply warm air from any desired source to a vehicle to dry the same after it has been washed and rinsed at stations *a* and *b*. In this instance the spray devices are supplied with warm 35 air through pipes 31 connected with a shell 32 surrounding a heater 33, a blower 34 being provided to force air through said shell to said spray devices.

Each of the aforesaid front and rear wheel 40 spray devices 27, 28 and 29, 30 consists of a vertically disposed pipe, provided, in the instance of devices 27, 28 with water outlet apertures 35, as shown in Figure 4, and in the instance of pipes 29, 30 with air spray 45 nozzles 36, the pipes at each operating station being relatively movable whereby they may be adjusted longitudinally of the machine towards and away from each other to be disposed in substantially the same desired predetermined relation to vehicles of 50 different length.

In the present embodiment of my invention the rear wheel spray devices or pipes 28-30 have fixed locations near the entrance ends of the respective operating stations *a*, *b* and *c*, and are rigidly supported in any preferred manner, as, for example, by having their lower end portions secured to plates 37 affixed to and projecting outward from the track rails 17.

Associated with each rear wheel spray device or pipe 28-30 is a stop device in the form of a roller 38 on one end of an arm 39 that is intermediately pivoted to a fixed bracket or support 40 and the other end of

which is weighted as at 41 whereby said roller is disposed normally across the path of movement of a wheel of a vehicle, so as to engage said wheel and halt the vehicle in predetermined relation to said spray device.

Each of the pipes 27, 29 constituting the front wheel spray devices is suspended for swinging movement in any preferred manner, as, for example, by being flexibly connected by a short length of hose 42 to its supply pipe, and by means of a weight 43 or equivalent means, is maintained normally at its limit of swinging movement towards its associated rear wheel spray device 28 or 30, preferably against a stop 44, as shown at each of the operating stations *a*, *b* and *c* in Figure 1 of the drawings.

Affixed to each front wheel spray device or pipe 27-29, at or near the lower end of the latter, is a bracket 45, and pivoted to this bracket for swinging movement in a horizontal plane is an arm 46 carrying at its free end a roller 47 that is held normally across the path of movement of a wheel of a vehicle passing through the machine by yieldable means such as a coil spring 48 connecting arm 46 with bracket 45, said spring being of such strength that a greater force is required to swing the arm 46 to a position with the roller 47 disposed out of the path of movement of a wheel of a vehicle passing through the machine, as shown in dotted lines in Figure 8, than the force necessary to swing the spray pipe away from limit stop 44 against another limit stop 49.

The operation is apparent and as follows: With the conveyor belts in operation and moving in the direction of the arrow *d* in Figure 1 of the drawings, operators at opposite sides of station *a* lift the weighted arms 39 to swing rollers 38 downward as shown in Figure 7, out of the path of movement of the front wheels of a vehicle entering the machine and hold said arms lifted until the front wheels of the vehicle pass by same, when the arms are released and weights 41 swing the rollers 38 to the position shown in Figure 6 to engage with the rear wheels of the vehicle and halt the same. If the vehicle is longer than the normal distance between the front and rear wheel spray devices, its front wheels will engage with the rollers 47 and swing the front wheel spray devices or pipes away from the rear wheel spray devices or pipes until the vehicle is halted by the rear wheels thereof engaging with rollers 38, when both the front and rear spray devices will be disposed in substantially the same predetermined relation to the front and rear wheels of the vehicle, the adjustment of the spray devices to predetermined positions with respect to vehicles of different length thus being automatic as is manifest.

The conveyor belts continue to move after the vehicle has been halted and since the vehicle cannot move forward through the machine and wheels are rotated backwards by said conveyor which obviously facilitates the cleaning action of water issuing from the apertures 35.

When the vehicle has remained at station *a* over a desired period of time, the arms 39 are again lifted and it is moved bodily by the conveyer belts towards station *b*, during which movement the front wheels thereof of acting against rollers 47 swing the front spray devices until they reach the limit stops 49, when said rollers are moved outward against the force of the springs 48 by the front vehicle wheels and said wheels thus pass by the same. The weights 43 then swing the front spray devices to the rear 20 where they are engaged by the rear wheels of the vehicle as the latter is carried along the conveyor belts and the operation just recounted is repeated. The complete operation set forth in the foregoing then occurs at 25 stations *b* and *c*.

Preferably each pipe constituting the front and rear wheel spray devices at stations *a* and *b* is provided with branch fender spray pipes 50, and, as shown in Fig. 1, the machine may be placed in a pit to dispose the conveyor belts at the level of the surface over which vehicles travel to enter the machine, or, as shown in Figure 5, inclined approaches 51 may be provided at the ends of 35 the machine if it is desired to position the conveyor belts at an elevation.

I claim:—

1. In a vehicle washing machine, a movable spray device, stop means to halt a vehicle passing through the machine, and means whereby said spray device is moved by a vehicle passing through the machine to a predetermined position with respect to a portion of the vehicle.

2. In a vehicle washing machine, front and rear spray devices, one of which is movable towards and away from the other, and a member carried by said movable spray device engageable by a portion of a vehicle passing through the machine whereby such spray device is moved with the vehicle in a predetermined relation with respect thereto, said member being yieldable whereby the vehicle may pass by the same when the movable spray device is held against movement.

3. In a vehicle washing machine, a spray device, and a stop engageable with a portion of a vehicle passing through the machine to halt the vehicle in predetermined relation to said spray device, said stop being movable to a released position and being positioned to be held released by a vehicle passing through the machine.

4. In a vehicle washing machine, a movable spray device, and a member carried by

said movable spray device engageable by a vehicle passing through the machine whereby said spray device is moved with said vehicle, said member being yieldable and positioned to be forced out of the path of the vehicle by the vehicle during its passage through the machine.

5. In a vehicle washing machine, a spray device, and a stop device to halt a vehicle passing through the machine in predetermined relation to said spray device, said stop device being releasable and being weight operated to vehicle stopping position.

6. In a vehicle washing machine, front and rear spray devices one of which is movable within predetermined limits towards and away from the other, means normally maintaining said movable spray device at its limit of movement in one direction with respect to the other spray device, and means operable by a vehicle passing through the machine to move said movable spray device with the vehicle in a predetermined relation thereto.

7. In a vehicle washing machine, a movable spray device, a member thereon engageable by a vehicle passing through the machine whereby the spray device is moved in a predetermined relation with the vehicle, and a spring holding said member normally in a position to be engaged by the vehicle whereby the member may yield to permit the vehicle to pass by the same when the spray device is held against movement.

8. In a vehicle washing machine, a conveyor upon which the wheels of a vehicle are adapted to rest, means for driving said conveyor whereby the vehicle is carried through the machine and whereby the wheels thereof are caused to rotate when the vehicle proper is held against movement, a spray device, and a stop in the form of a roller engageable with a wheel of a vehicle resting on said conveyor whereby the vehicle is halted in predetermined relation to said spray device.

9. In a vehicle washing machine, a conveyor upon which the wheels of a vehicle are adapted to rest, means for driving said conveyor whereby the vehicle is carried through the machine and whereby the wheels thereof are caused to rotate when the vehicle proper is held against movement, a movable spray device, and a member carried by said spray device engageable by a vehicle passing through the machine whereby the spray device is moved to a predetermined position with respect to the vehicle, said member consisting of a roller engageable with a wheel of the vehicle.

10. In a vehicle washing machine, a movable spray device, a member thereon engageable by a vehicle passing through the machine whereby the spray device is moved in a predetermined relation with the vehicle, yieldable means holding said member nor-

mally in a position to be engaged by a vehicle, a stop against which the spray device is adapted to abut when moved by a vehicle passing through the machine, whereby such 5 vehicle may overcome said yieldable holding means and pass by said member, and means holding said spray device normally spaced from said stop.

11. In a vehicle washing machine, in combination, a vehicle trackway in the form of 10 an endless carrier on which a vehicle is

adapted to move through the machine, a cleaning device adjacent to said carrier, and a releasable positive stop device located in the path of a portion of a vehicle moving through the machine on said carrier for stopping the vehicle in a predetermined position with respect to said cleaning device. 15

In testimony whereof I hereunto affix my signature.

HOWARD S. GIBSON.
